US0D1061487S

(12) **United States Design Patent** (10) **Patent No.:** **US D1,061,487 S**
(45) **Date of Patent:** **** Feb. 11, 2025**

(54) **ANTENNA**

(71) Applicant: **Samsung Electronics Co., Ltd.**, Suwon-si (KR)

(72) Inventors: **Hyungjun Koo**, Suwon-si (KR); **Jihee Kwak**, Suwon-si (KR)

(73) Assignee: **SAMSUNG ELECTRONICS CO., LTD.**, Gyeonggi-Do (KR)

(**) Term: **15 Years**

(21) Appl. No.: **29/854,361**

(22) Filed: **Sep. 23, 2022**

(30) **Foreign Application Priority Data**

Jul. 25, 2022 (KR) 30-2022-0029890

(51) **LOC (15) Cl.** **14-03**

(52) **U.S. Cl.**

USPC **D14/230**

(58) **Field of Classification Search**

(57) **CLAIM**

The ornamental design for an antenna, as shown and described.

DESCRIPTION

FIG. 1 is a front perspective view of an antenna, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in FIG. 3 depict portions of an antenna that form no part of the claimed design.
